UNITED STATES PATENT OFFICE.

HARRY M. MARTYN, OF UTICA, NEW YORK, ASSIGNOR TO WILLIAM L. FOLEY AND CHESTER W. DAVIS, OF UTICA, NEW YORK.

AUTOMATIC ENGINE-STOP.

No. 839,779.

Specification of Letters Patent.

Patented Dec. 25, 1906.

Application filed March 5, 1906. Serial No. 304,393.

To all whom it may concern:

Be it known that I, HARRY M. MARTYN, a citizen of the United States, residing at Utica, in the county of Oneida and State of New York, have invented certain new and useful Improvements in Automatic Engine-Stops, of which the following is a specification.

My present invention relates to an improvement in mechanism for automatically stopping an engine when it attains too high a rate of speed—as, for instance, when the driving-belt breaks or the regular governor-belt breaks or for some other cause—and also includes means for stopping the engine from some remote point in case of accident or emergency.

In the drawings, Figure 1 shows a side elevation of an engine equipped with my mechanism, including a diagram of the main electric circuits employed in the construction. Fig. 2 shows in detail by diagram the complete arrangement of electric circuits employed in connection with the construction as well as other details of construction. Figs. 3 and 4 show in section details of a three-way cock employed in the construction in two of its positions. Fig. 5 shows, mostly in section, details of inlet and exhaust openings in connection with the actuating and regulating cylinder of the construction.

Referring to the reference letters and figures in a more particular description, 1 indicates the engine to which my improved mechanism is illustrated as being applied.

2 is the regulating-governor provided on the engine, while 3 is the steam-supply pipe, and 4 the throttle-valve in said pipe.

5 indicates the crank-shaft, and 6^a the rod by means of which the valve mechanism 1^a is controlled from the governor 2. The valve 4 is provided with a hand-wheel 4^a, by means of which it can be manually operated, and with a reel 4^b, receiving one end of the small cable 6. This cable 6 after passing over suitable pulleys to bring it to the desired point is connected with the piston-rod 7 of the elongated cylinder 8 either directly or through the medium of multiplying-pulleys, as shown. The cylinder 8 is mounted on a fixed support. The arrangement of the connections just described is such that when the piston-head 7^a is moved to the bottom of the cylinder the cable 6 is drawn from the reel 4^b,

which serves to close the throttle-valve 4. At the upper end of the cylinder 8 there is 55 connected a pipe 9 for supplying water or similar pressure fluid to the cylinder to actuate the piston 7^a in its downward movement, and this pipe may be connected with the water-space of a boiler or with a water-works 60 system or other source of supply which will furnish a constant pressure. In the pipe 9 there is provided a three-way cock 10, which has the branch 11, serving as an exhaust from the cylinder 8. The plug 10^a of the 65 three-way cock is provided with passageways, as shown in Figs. 3 and 4. When in the position shown in Fig. 3, the passage is open from the cylinder to the exhaust-pipe 11, while the supply is cut off. When the 70 plug is in the position shown in Fig. 4, the passage is open from the supply to the cylinder and the passage to the exhaust 11 is cut off.

The movable plug 10^a of the stop-cock is 75 connected with a segmental lever-piece 12, having stops 13 and 14 at either corner thereof, and between these stops extend the weight-lever 15, which is also mounted to turn freely on the head of the plug 10^a and 80 has a limited movement between the stops 13 and 14 independent of the movement of the plug of the stop-cock. The weight-lever 15 is provided with a weight 16, secured thereon, and there may also be provided a 85 starting-spring 17, secured on a suitable fixed support. The weight-lever 15 is held in its normal position by an electrically-operated catch 18, which catch is pivoted on a fixed support and is adapted to be released 90 by the electromagnet 19. The electromagnet 19 is in electric circuit with a dynamo or other suitable source of electricity, as 20, and a circuit making and breaking contrivance, including a fixed contact 21 and a movable 95 contact-lever 21, operated by a governor 23, which governor is driven in any suitable way from the engine to be controlled, preferably by a belt, as 24. The lower end of the cylinder 8 is provided with an exhaust-opening 100 controlled by an adjustable needle-valve 25 and is provided with an intake-opening controlled by a valve 26 as against exhaust through said intake-opening. There may also be provided in the lower end of the cylinder 105 an adjustable stop in the nature of a

screw 27, which will limit the downward movement of the piston and piston-rod.

The operation of the mechanism thus far described is as follows: The stop-cock being 5 in the position shown in Fig. 3, with the operating parts in the position shown in Fig. 2 and held by the catch 18, the engine may be 10 put in motion by opening the valve 4, which opening is accomplished by rotating the stem 15 of the valve by the hand-wheel 4^a. In so doing the cable 6 is wound onto the reel 4^b to some extent, and the piston 7^a is moved to or toward the top of the cylinder 8 more or less, depending on the arrangement of the 20 parts. When the piston is moved upwardly in the cylinder 8, air is readily let in through the valve 26 under the piston, and its upward movement is not impeded. The engine being in motion, of course the governor 25 will be also placed in motion. If the engine attains such a high speed as to move the contact-lever 41 up into engagement with the contact button or piece 21, an electric circuit is established through the dynamo 20 30 and the electromagnet 19, causing the release of the catch 18. When released, the weight-lever 15 either through its own natural position or through the influence of the starting-spring 17, or both, swings freely toward the 35 right, as shown in Fig. 2, attaining some little momentum before the lever 15 comes into engagement with stop 13. When it does engage the stop, it continues the movement, carrying with it the valve-lever 12 and the valve-plug 10^a until the latter is turned from the position shown in Fig. 3 to that shown in Fig. 4. There will preferably be arranged on a fixed support a stop 30, which will limit the movement of the weight and lever when it is 40 moved far enough to accomplish the desired purpose. When the stop-cock has been open to the position shown in Fig. 4, the pressure is applied to the upper side of the piston 7^a, forcing it downwardly toward the 45 bottom of the cylinder. The first portion of this operation will be comparatively rapid, inasmuch as the air under the piston will first be compressed to some considerable extent before it tends to materially retard the 50 movement of the piston. As the piston approaches the bottom of the cylinder its movement will be retarded, and the rapidity with which it will finally reach its lowest position will be determined by the size of the exhaust-opening in the lower end of the cylinder, which, as before mentioned, is under the control of the needle-valve 25. As the piston descends it draws on the cable 6, and as the cable unwinds from the drum 4^b of course it 55 rotates the stem of the valve and closes the valve. The fact that the stop was caused by the mechanism under control of the governor 23 will be indicated on the annunciator 20^a, for it will be noted that one branch of 60 this circuit, which includes the electromag-

net 19, passes through that instrument. Before the engine can be again started the weight-lever 15 must be placed back in its original position and caught by the catch 18, in which operation the stop-cock will be 70 turned to shut off the supply and allow the contents of the cylinder 8 to be exhausted.

In addition to making the electrical contact with the button or contact-point 21 the lever 41, controlled by the governor, is adapted to make two other electrical connections, one of which is with the contact button or point 40 when the lever 41 is at its lowest position and when the engine, or more particularly the governor 23, is at rest and one 80 with the contact point or button 22, which is a contact adapted to be made when the engine is running above normal speed and less than dangerous.

The contact between the lever 41 and the 85 contact point or button 40 is utilized as follows: 40 and 41 are in circuit with the dynamo 20 or other suitable source of energy with an incandescent colored lamp G, arranged on a suitable board M in the engine-room, preferably with an ordinary electric bell H, so that when contact is made at the point between lever 41 and button 40 there will be a light shown at G and an alarm sounded at H. The contact made between 90 lever 41 and contact point or button 22 is utilized as follows: 41 and 22 are in circuit with dynamo 20 and a colored lamp R arranged on the base or backing board M, before mentioned. On the board M, before mentioned, there is also provided an electromagnet N, which electromagnet N is in circuit with still another electric light W on the base-board before mentioned and with the dynamo 20. The armature n of electromagnet 105 N serves as an electric switch and is normally moved away from the electromagnet by spring S. When so moved away, it makes an electric contact completing a circuit including the bell H and the battery P and 110 switch E. In connection with the circuit which includes the electromagnet 19 and which is adapted to be closed at one point by the lever 41 and contact 21 there are other means provided for closing the same circuit— 115 viz., a number of manually-operated switches T. These switches are preferably arranged in a branch from the circuit, including electromagnet 19, and at one point the circuit is subdivided to provide independent contacts 120 for said switches and pass through the annunciator, respectively. These switches may be respectively located at any desirable points—as, for instance, in the several floors or in several different rooms of a factory. 125

Various utilities of the mechanism last described may be mentioned as follows: At all times when the dynamo 20 is in operation and furnishing the desired electric energy current will be supplied to the lamp W and to 130

the electromagnet N, which, through its switch-armature *n*, maintains the mechanism in what might be denominated the normal running condition, and the attendant knows 5 that the equipment is in perfect running order, ready for action, by the fact that the lamp at W is lighted. In case the dynamo 20 or the electric wiring should fail the current would fail in the electromagnet N, 10 and the armature *n* would immediately be shifted over, completing the circuit through the battery P and the bell H. By hearing the bell H sounded and noting that the light W has become extinguished the attendant is 15 informed at once that the trouble exists in the fact that there is no electric energy in the system for operating the automatic stop-motion on the engine. In such case the emergency-battery may be temporarily substituted for 20 the dynamo 20 by throwing over the switch O from the position in which it is shown in full lines in Fig. 2 to its opposite closed position. In case the continuous ringing of the bell H becomes bothersome it may be stopped 25 by shifting the switch E. In case the engine is running under normal conditions the lever 41 will be maintained in an intermediate position between contacts 40 and 22. In case of the engine attaining an abnormal speed 30 the contact is made between 22 and 41, which completes the circuit through light R and alarm-bell H. In case of still higher speed the circuit is completed through electromagnet 19. The automatic stop mechanism can 35 also be thrown into operation by any one of the numerous switches T. In case the engine has been stopped by the use of any of the switches T the attendant or engineer can determine the fact by examining the annuncia- 40 tor. When the governor 23 comes to a stop from the belt 24 breaking or otherwise, the lever 41, dropping in a position to make electric contact with 40, the lamp G will be lighted and the bell H sounded. In case of a 45 stoppage for the night or noon-hour, for instance, the engineer or attendant will throw open the switches O and E. Upon starting

the engine these switches should be closed, of course.

It is evident that numerous changes in and 50 from the construction herein described may be made without departing from the spirit of my invention. One of these which I would like to particularly note is that instead of controlling the engine from the throttle-valve 4 55 it may be controlled through the engine valve-gearing by dispensing with the connection to valve 4 and continuing the cable 6 in the manner indicated in dotted lines in Fig. 1 and indicated by 6^b, in which latter case the connection 6^b is made to a lever on the governor 2, 60 which controls the valve-gear to shut off the steam in the same manner as the governor 2 controls the same.

I claim—

1. The combination in a safety appliance for engines of a cylinder and piston, a cock controlling a pressure fluid supplied to said cylinder, means for automatically operating said cock, an electrically-controlled catch restraining the operation of said means, a circuit-closer in circuit with electrically-controlled catch, and a governor operating said circuit-closer from the engine, substantially as set forth. 75

2. The combination in an automatic stopping device of the steam-controlling valve, the cylinder and piston, a connection from the piston to the said steam-controlling valve, a cock controlling the supply of pressure fluid to the cylinder, means for automatically operating said cock, a catch for securing the said operating means in normal, position, and automatically and manually operated contacts for closing the circuit and releasing said catch, substantially as set forth. 80 85

In testimony whereof I have signed my name to this specification in the presence of two subscribing witnesses.

HARRY M. MARTYN.
